(57) **CLAIM**

The ornamental design for a display screen or portion thereof with a graphical user interface for communication, as shown and described.

DESCRIPTION

The sole FIGURE is a display screen or portion thereof with a graphical user interface for communication showing the new design.

The broken lines shown in the drawing illustrate portions of the display screen or portion thereof with a graphical user interface for communication which form no part of the claimed design.

@AndrewJensen it's not currently part of Share Everywhere but most of the plumbing is already in ... [View more](#)

That would be great. Any concerns with that @CodySmith?

Greg Allen 8:31 AM

@AndrewJensen - Who could our designer talk to in order to make sure we're on the same page?

AndrewJensen 8:31 AM

@Greg Allen I would recommend talking to @Ken Kirkland about it.

Greg Allen 8:32 AM

@NathanThorneon, could you talk to Ken?

Nathan Thorneon 8:34 AM

Greg Allen
@NathanThorneon, could you talk to Ken?

Yes I can do that.

Cody Smith 8:45 AM

Greg Allen
That would be great. Any concerns with that @CodySmith?

Sounds good!

Jacob Carter 9:02 AM

The "mark all as read" button isn't working in demo this morning - Mac native app.
